No. 836,128.

PATENTED NOV. 20, 1906.

J. F. McELROY.
CEMENT FENCE POST.
APPLICATION FILED FEB. 20, 1906.

UNITED STATES PATENT OFFICE.

JOHN F. McELROY, OF CEDAR RAPIDS, IOWA, ASSIGNOR TO PYRAMID POST & POLE COMPANY, OF CEDAR RAPIDS, IOWA, A CORPORATION OF SOUTH DAKOTA.

CEMENT FENCE-POST.

No. 836,128.

Specification of Letters Patent.

Patented Nov. 20, 1906.

Application filed February 20, 1906. Serial No. 302,028.

To all whom it may concern:

Be it known that I, JOHN F. McELROY, a citizen of the United States, residing at Cedar Rapids, in the county of Linn and State of Iowa, have invented certain new and useful Improvements in Cement Fence-Posts, of which the following is a specification.

This invention relates to fence-posts having a metallic framework embedded in a cement body, and has for its object to strengthen the post as a whole and at the same time reduce to as great an extent as possible the amount of cement necessary to be used and cheapen the resulting fence-post to that extent.

Another object is to provide a suitable attaching-surface for the fence-wires and an easy and convenient means of attaching the wires thereto at suitable points.

Another object of the invention is to improve the construction and arrangement of the framework embedded within the cement and to improve generally the construction and appearance of the fence-post as a whole.

The invention consists in the features of construction and combination of parts hereinafter described and claimed.

In the drawings illustrating the invention, Figure 1 is a side elevation of the fence, showing two posts and the fence-wires attached thereto, Fig. 2, a perspective view of a section of fence-post, showing the cement body partially broken away; Fig. 3, a sectional elevation cut from front to rear of the post, and Fig. 4 a cross-sectional face view taken on line 4-4 of Fig. 3.

The post is of substantially triangular shape, tapering from bottom to top, and comprises a framework consisting of upright rods 1, arranged in substantially parallel relation to the strand-wires of the fence, and a third upright rod 2, located at the rear of the front upright rods, the three rods forming the points of a substantially equilateral triangle. The rods are connected at suitable intervals by means of wire braces 3, which are provided with loops or coils 4, surrounding the front and rear rods, respectively, for binding the rods of the framework together. The rods 5 are embedded within a cement body 5, the shape of which conforms in a general way to the arrangement of the rods comprising the framework. The cement body has two front

flanges 6, separated by an intermediate channel or depression 7, and the body is further 55 provided with a rear flange 8, separated from the front flanges by means of channels or depressions 9. The flanges are preferably rounded in contour, and the post as a whole is devoid of sharp corners or angles, which 60 would tend to be broken or worn off during continuous usage.

The front flanges have extending diagonally therethrough a plurality of bracket or staple holes 11, which extend from front to rear 65 of the front or attaching flanges obliquely upward through the flanges opening at the rear sides thereof. The holes on the companion attaching-flanges are suitable in number to provide for considerable adjustment of the 70 fence-wires and are preferably arranged in staggered relation to one another, and the front openings are close to the center of the depression or channel between the flanges. In other words, the staple or bracket holes 75 extend obliquely through the attaching-flanges and converge from rear to front toward one another. The holes allow the passage therethrough of brackets or staples 12, which outwardly project from the flanges 80 and are provided on their attaching ends with hooks 13, adapted to embrace the strand-wires of the fence, and the brackets or staples ordinarily project out from the attaching-flanges of the post a sufficient distance to 85 bring the hooked ends of all the staples or brackets into vertical alinement with one another immediately in front of the center of the post. The rear ends of the staples after insertion are turned down to form a securing 90 bend or hook 14, which abuts against the rear face of the attaching-flange of the post.

In use strand-wires 15 are secured to the posts by means of the hooked ends of the attaching brackets or staples which are inserted through the holes in the post and afterward bent down to secure them against displacement. By forming the attaching-holes in the manner specified the weight of the fence-wires will always tend to hold the 95 brackets or staples tightly in place, since there will be a constant downward pull, forcing the hooked rear ends of the staples into firm bite or contact against the rear faces of the posts. The holes being arranged 100 in converging relation to one another can be

drilled through the thinnest portions of the fence-post, thereby enabling the use of short brackets or staples, which would be impossible if a fence-post of the ordinary shape were employed. Furthermore, the oblique relation of the brackets with respect to the strand-wires which they support greatly reduces the strain brought to bear upon the bent-over rear end of the staple and prevents the end from being bent or sprung by the strain of the fence-wire and being pulled out bodily, which might be the case if a direct strain were brought to bear upon the rear end of the bracket or staple. By arranging the holes in staggered relation the distance between the strand-wires of the fence can be changed or modified as occasion demands, and the staggered arrangement of the holes prevents the fence-post from being unduly weakened at any point. The attaching-flanges provide a firm contact for the strand-wires, and the rear or reinforcing flange is located at an intermediate point, where it will have the highest efficiency for reinforcing purposes. As is well known, a flanged or channeled structure possesses great strength and rigidity, and in the present case the fence-post as a whole will be much stronger than a post of the same weight of square, round, or other ordinary formation. The pyramidal or tapered formation of the post distributes the strain in a suitable manner and results in a post which is light, strong, and durable and very attractive in appearance.

What I regard as new, and desire to secure by Letters Patent, is—

1. A fence-post of substantially triangular formation having front attaching-flanges and an intermediate rear reinforcing-flange, the attaching-flanges having pierced therethrough holes arranged in converging relation to each other from rear to front for the passage of attaching-brackets, substantially as described.

2. A fence-post of substantially triangular formation having front attaching-flanges and an intermediate rear reinforcing-flange, the attaching-flanges having alternately pierced therethrough holes arranged in converging relation to each other from rear to front for the passage of attaching-brackets, substantially as described.

3. A fence-post of substantially triangular formation having front attaching-flanges and an intermediate rear reinforcing-flange, the

attaching-flanges having alternately pierced therethrough holes arranged in staggered relation with respect to one another, said holes extending in a diagonally upward direction through the flanges and in a converging relation from rear to front with respect to one another for the passage of attaching-brackets therethrough, substantially as described. 6c

4. A fence-post consisting of metallic framework and a cement body having front attaching-flanges and a rear reinforcing-flange all arranged in radial relation with respect to the center of the post, the front flanges having extending therethrough a plurality of holes extending diagonally upward through the flanges and in converging relation from rear to front with respect to one another for the passage therethrough of attaching-brackets, substantially as described. 7c

5. A fence-post consisting of metallic framework and a cement body having front attaching-flanges and a rear reinforcing-flange all arranged in radial relation with respect to the center of the post, the front flanges having extending therethrough a plurality of holes extending diagonally upward through the flanges and in converging relation from rear to front with respect to one another, and attaching-brackets hooked at their forwardly-projecting attaching ends and turned down at their rear ends, substantially as described. 8c

6. A fence-post consisting of a metallic framework comprising three upright bars in triangular relation with respect to one another and a cement body within which the bars are embedded, said body having front attaching-flanges and an intermediate reinforcing-flange radially arranged with respect to the center of the post, the attaching-flanges being separated by an intermediate channel or depression and being provided with a plurality of staggered holes extending diagonally upward through the flanges and in converging relation from rear to front with respect to one another, and attaching-brackets provided at their forwardly-projecting ends with hooks and turned down at their rear ends to prevent withdrawal, substantially as described. 9c
